UNITED STATES PATENT OFFICE.

EUGENE H. TAYLOR, OF HYDE PARK, MASSACHUSETTS, ASSIGNEE, BY MESNE ASSIGNMENTS, TO CUSHMAN PAPER BOX MACHINE COMPANY, A CORPORATION OF MAINE.

GUMMING MECHANISM.

966,619.

Specification of Letters Patent. Patented Aug. 9, 1910.

Application filed June 9, 1906. Serial No. 321,032.

To all whom it may concern:

Be it known that I, EUGENE H. TAYLOR, of Hyde Park, the county of Norfolk, State of Massachusetts, a citizen of the United States, have invented a new and useful Improvement in Gumming Mechanism More Especially Adapted for Use in Paper-Box Making, of which the following is a specification.

10 The purpose of this invention is to insure the gumming of the blanks before they are folded.

In the class of machines for which the gummer is especially designed, the blanks 15 are placed in a hopper and each is then gummed before being delivered to the folding mechanism. A perfectly rigid gummer is not always effective for the purpose for the reason that the surface to be gummed is often not absolutely parallel with the plane 20 of the gumming surface so that the gummer will not come into proper contact therewith and portions of the surface will not be gummed at all.

25 My present invention relates to means for so supporting the gummer that it shall rock and so conform itself to such irregularities in the surface to be gummed.

30 My invention will be understood by reference to the drawings in which—

Figure 1 is a side elevation of a mechanism embodying my invention attached to a portion of a box machine of the character referred to, the box containing the gum 35 being shown in section. Fig. 2 is a plan of the gummer partly in section. Fig. 3 is an end view of the gummer and a portion of the supporting mechanism. Fig. 4 is a sectional view on the line 4—4 of Fig. 2. 40 Fig. 5 is a sectional detail on the line 5—5 of Fig. 2. Fig. 6 is a diagram showing in reduced scale the gummed surfaces produced by a gummer like that shown in Fig. 2 upon a box blank.

45 A is a portion of the side wall of the blank hopper of a box making machine. B is the gum tank suitably supported on said machine and C is the end of a rocker arm operated in a suitable manner to raise and 50 lower the gummer and so cause it to perform its functions. As the invention does not relate to the parts above specified nor to the positive movement of the gummer or the means for supporting and operating it, these 55 parts are not shown.

a, a¹ are guides on the side of the hopper A in which the rod D is reciprocated by the rocker arm C and the parts which operate it. This rod D also carries an arm d having at its end an eye d¹ which slides upon a guide 60 rod d² hung from the side wall of the hopper A. The lower end of the rod D is threaded and an adjusting nut d³ screws thereon, to raise and lower the horizontal arm E upon which the gummer is carried. For this purpose 65 the arm E is provided with a hub e which has a longitudinal extension upon one side of it. In this extension is a groove e¹ in which fits a lateral extension d⁴ from the nut d³. By this construction the parts are 70 easily put together and the turning of the nut d³ will positively raise and lower the arm E. A set screw e² locks the hub e and arm E in place when its position has once 75 been determined.

The gummer comprises two rectangular frames F, F¹ adapted to imprint upon the blank corresponding gumming surfaces such as are shown in Fig. 6 at F². The gummer is first submerged in the gum in the tank B 80 and is then lifted to imprint a gummed surface on the under blank in the hopper. To enable it to conform to irregularities in the surface of the blank it is rendered capable of movements independent of the reciprocating movement given to its supporting rods D and E; for example: a slight rocking movement about the axis of the rod E and a slight rocking movement around the axis of the rod H which is at right angles to 85 the rod E. The transverse rocking movement around the axis of the rod E will first be described:

G is a sleeve which is grooved on one side as at g to receive a collar h fixed on the shaft 95 H which carries the gumming frames F, F¹. This sleeve G is adjustable on the rod E so as to move the gummer toward and from the rod D for purposes of adjustment, and for this purpose the sleeve G is provided with 100 a slot g¹ in which engages a projection g² upon the nut g³ which turns upon the threaded extremity of the rod E, this construction being identical with that of the parts d² and e described above. The rod E 105 is grooved along its under side as shown at g⁴ and into this groove the screw g⁵ passes through the sleeve G. As will be seen from Fig. 5, this slot is slightly wider than the end of the screw so that a slight rocking 110

movement is allowed to the sleeve G and the parts supported thereon. This gives the necessary play about the axis of the rod E, the shoulders or side walls of this groove 5 serving as stops to prevent this motion from being too great.

The rod H furnishes the cross axis about which the gumming frames turn and it also serves as a means of adjusting the frames 10 toward and from each other. For this latter purpose the rod H is provided with threads h^1 at each end, one of these threads being a right-handed and the other a left-handed thread. From the outer wall of 15 each frame there project downward two straps f^2 the ends of which are connected by a screw f^3 and between each pair of straps is a nut f^1 through which a threaded end of the rod H passes. The screw f^3 serves to 20 clamp the nut between the straps. A bearing f^4 is also provided in the wall of each frame through which the rod H also passes. The rod H is also provided with a thumb head h^2 by which it may be turned to cause 25 the frames to approach or separate. In addition the sleeve G carries arms J, J^1 , each of which has at its end a collar j , j^1 , through which the rod H passes and from which project laterally arms j^2 . These arms 30 extend outward from the medial line of the frames F, F^1 to a position underneath their walls, as shown in Figs. 3 and 4, and as there shown there is normally a slight space between the top of the extremity of each arm 35 and the opposing surface of the gumming frame. These arms j^2 are rigid and, as the frames are free to turn upon the rod H, one edge or the other of the frame may strike upon the extremity of one of these rods as 40 circumstances require. The collar h keeps the rod H from endwise movement.

The main feature of my invention is mounting the gummer so that it will conform to the plane of the under surface of 45 the blanks, and it is evident that there are other means for mounting the gummer, than those above described, whereby the desired result may be accomplished. In some cases the mounting of the gummer upon a single 50 axis may be sufficient, but the use of two cross axes is preferable because of the greater range of motion it allows the gummer; a range practically universal. Moreover, in some cases each gumming frame 55 may be supplied with its own transverse axis if thought best. The details of construction are immaterial.

It is obvious also that this gummer, while especially fitted for gumming box blanks, 60 may if its gumming surface be properly shaped be used for gumming envelop blanks or other surfaces.

What I claim as my invention is:—

1. In a gumming mechanism, a horizontal 65 shaft, a gumming frame mounted to oscil-

late thereon, said shaft carrying arms located below said frame and adapted to engage said frame as it oscillates and limit its oscillation.

2. In a gumming mechanism, a horizontal 70 shaft, gumming frames located to be oscillated thereon, and means for adjusting said frames simultaneously on said shaft.

3. In a gumming mechanism, a horizontal 75 shaft, gumming frames located to be oscillated thereon, and means for adjusting said frames simultaneously toward and from each other on said shaft.

4. In a gumming mechanism, a horizontal 80 shaft and a gumming frame having a bar 85 adapted to encircle said shaft and allow said frame a limited oscillating movement thereto, and means adapted to allow said first-named shaft to oscillate about said second-named shaft, as set forth.

5. In a gumming mechanism, a gummer 90 mounted on two axes at right angles to each other and provided with stops whereby the degree of oscillation of said gummer around 95 said axes may be limited in combination with said axes.

6. In a gumming mechanism, means for supporting gummers comprising a horizontal 95 rod, a pair of gummers located one on each side of said rod and adapted to have a limited movement about said rod, as described.

7. In a gumming mechanism, means for 100 supporting gummers comprising a horizontal rod, gummers located on each side of said rod and adapted to oscillate thereon, and means for supporting the said gummers upon said horizontal rod comprising a rod 105 running at right angles thereto.

8. In a gumming mechanism, means for 110 supporting gummers comprising a horizontal rod, a second horizontal rod at right angles thereto, means for supporting said second horizontal rod upon said first rod, whereby it may rock, and means for supporting gummers upon said second horizontal rod whereby they may rock thereon, in combination with said gummers, as set forth. 115

9. In a gumming mechanism, a reciprocating rod, a horizontal rod carried thereby, 120 gummers, means for supporting said gummers upon said horizontal rod adapted to oscillate thereon, and means for adjusting said gummers to and from said reciprocating rod, as described.

10. In a gumming mechanism, a vertically 125 reciprocating rod, a horizontal rod adjustably supported thereon, means for supporting gummers upon said horizontal rod whereby they may oscillate upon said rod and means whereby they may be adjusted toward and from said vertically reciprocating rod, said means comprising a rod at 130

right angles to said horizontal rod, and means whereby the gummers located thereon may be adjusted toward and from each other, in combination with said gummers, as 5 described.

11. In a box-making machine, in combination with a gum box, a gummer, and means whereby said gummer is adjusted comprising a rod, a sleeve supporting said 10 gummer movable along said rod, a portion of said rod being threaded, and a nut adapted to engage said sleeve and turn upon said threaded portion of said rod.

12. In a box-making machine, in combination with a gum box, a gummer, and means whereby said gummer is adjusted comprising a rod, a sleeve supported in said 15 gummer movable along said rod, a portion of said rod being threaded, and a nut adapted to engage said sleeve and turn upon said threaded portion of said rod, said nut and said sleeve being connected whereby the rotation of said nut will move said sleeve and its gummer in either direction along said 20 rod.

13. In a box-making machine, in combination with a gum box, a gummer, and means whereby said gummer is adjusted comprising a rod, a sleeve supporting said 30 gummer movable along said rod, a portion of said rod being threaded, and a nut adapted to engage said sleeve and turn upon said threaded portion of said rod, and means for locking said gummer from movement along said rod after it has been adjusted. 35

14. In a box-making machine, in combination with a gum box a gummer, and means whereby it may be adjusted comprising a threaded rod, a hub movable thereon, said hub having a circumferential grooved 40 extension and a nut running upon the threaded portion of said rod and having a lateral extension engageable with the groove in said hub, as and for the purposes set forth.
